GRACE B. CATTELL, OF PORTSMOUTH, OHIO

GARTER

Application filed May 16, 1932. Serial No. 611,694.

The present invention relates to ladies' apparel and has for its object the provision of a simple, neat and comfortably fitting garter whereby the stockings may be supported without being liable to be torn or otherwise mutilated by the garter and the corset will be held smoothly to the figure. The invention is illustrated in the accompanying drawing and will be hereinafter fully set forth and 10 defined.

In the drawing, Figure 1 is a perspective view showing the device as it appears when worn,

Fig. 2 is an enlarged perspective view of 15 the device removed,

Fig. 3 is an enlarged perspective view of the foundation of the device,

Fig. 4 is a detail section on the line 4—4 of Fig. 3.

In constructing a garter according to the present invention, there is provided a limb-encircling band consisting of a strap 1 of elastic webbing and a similar strap 2 of the same material, the only difference between the 20 two straps being in their length. These straps are disposed end to end and the ends are connected by triangular sections of inelastic fabric, indicated at 3, the sides of these inelastic connecting sections converging 25 downwardly and the sections being made preferably in two plies, as best shown in Fig. 4. Between the upper portions of the two plies of these connecting sections 3, I dispose the lower end of a strap 4 of elastic webbing and to the upper ends of these straps 4 are secured inelastic tabs 5 which are each provided with a button hole 6 whereby it may be engaged over the studs or other fasteners at the ends of the supporters 7 which are secured 30 to and depend from the corset, as shown in Fig. 1. The tabs 5 are secured to the upper ends of the straps 4 by stitching and the inelastic inserts or gussets 3 are secured to the lower ends of the straps and to the meeting ends of the sections 1 and 2 by

stitching, as shown. To complete the article and give it an attractive appearance, the entire article, except the tabs 5, is covered with finishing material which may be silk or ribbons according to the fancies of the users. 50 This finishing material, indicated at 8, is preferably shirred and upon the outer surfaces of the gussets or triangular members 3 are preferably attached rosettes, indicated at 9.

The manner of arranging the device will be understood at once upon reference to Fig. 1. When in place, the corset will be held firmly in the desired smooth position without discomfort to the wearer and the stockings may 60 be held to the limbs without undue stress. The elastic suspending straps and encircling band will permit the device to yield to the movements of the wearer without chafing and the inelastic gussets will hold the article firmly in place and resist any tendency to shift around out of place. The device is exceedingly simple and may be produced at a low cost. In use, it has been found highly efficient for the purposes for which it is designed. 70

Having thus described the invention, I claim:—

A garter comprising an encircling band 75 consisting of straps of elastic material, substantially triangular gussets consisting of plies of inelastic fabric attached to and between the meeting ends of the elastic straps, the side edges of the gussets converging downwardly, elastic suspending straps having their lower ends secured to and between the plies of the gussets, inelastic tabs secured to the upper ends of the elastic suspending straps, and a finishing cover applied to the entire area of the encircling band including 80 the gussets and the suspending straps.

In testimony whereof I affix my signature.
GRACE B. CATTELL. [L.S.]
